WASHING MACHINE CYLINDER BALANCING APPARATUS

Leo M. Kahn and Edwin Ellner, New York, N. Y.; said Ellner assignor to said Kahn

Application May 31, 1946, Serial No. 673,680

24 Claims. (Cl. 74—573)

1

This invention relates to damp drying systems for laundry machines wherein the extraction of washing fluid from the washed articles is effected through high speed rotation of a perforated cylinder.

As was described in the prior and sole application of Leo M. Kahn Serial No. 620,038, filed October 3, 1945, wherein many of the structural details of the instant washing machine were disclosed, the drying of articles in machines of this type depends upon the generation of the centrifugal force accomplished by high speed rotation of the cylinder so as to eject the wash water through its perforations. However, the generally unsymmetrical distribution of the articles, particularly in a horizontal axis cylinder, often produces severe vibration which imposes a limit upon the speed of rotation and affects thereby the degree and time of drying. The above application Serial No. 620,038 was directed to the provision of peripherally disposed pockets to which was applied a counterbalance weight in the form of water so as to neutralize the effect of improper weight distribution within the cylinder. In addition, the means chosen to supply the counterbalancing water to the proper pockets involved an empirical process wherein the effects of adding the water arbitrarily were measured in terms of increased or reduced vibration of the rotating cylinder. The instant application, however, has as its principal object the effective identification of a particular portion of the cylinder in which the overweight occurs and the automatic application of weight counterbalance material to neutralize such overweight and secure a satisfactory rotating balance.

Another object of this invention is to select and momentarily isolate spaced peripheral portions of the rotating cylinder and simultaneously test such portions for unbalance. Such selection and isolation is produced by means synchronized with the rotation of the cylinder. Allied with this object is the provision of means to continue the application of counterbalancing forces to the correct portions of the rotating cylinder notwithstanding continued rotation whereby other portions of the cylinder are presented for unbalance testing. However, when the correct portion has already been established, the continued rotation does not have the effect of either momentarily discontinuing such application or shifting it to other and incorrect portions of the cylinder.

Another object of this invention is to provide a series of spaced peripheral pockets on a washing machine cylinder combined with means to apply

2

a counterbalance to more than one of the pockets simultaneously according to the site of unbalance in the cylinder. Thus, where the unbalance can not be corrected by injecting material in only one of the pockets, it may be secured by so treating a plurality of the pockets.

Still another object of this invention is to produce a balancing system for rotating washing machine cylinders which is simple, economical to manufacture and requires a minimum of operating parts.

Other objects of our invention will be apparent from the following description, it being understood that the above general statements of the objects of our invention are intended to describe and not limit it in any manner.

Referring to the drawings:

Fig. 1 is a side view in elevation, partly in section, of a preferred embodiment of the instant invention.

Fig. 2 is an enlarged, fragmentary, cross sectional view of the valved weight injecting end of the machine.

Fig. 3 is a cross sectional view taken along the line 3—3 of Fig. 2.

Fig. 4 is a schematic circuit diagram of the electrical controls for applying the counterbalance forces.

Fig. 5 is a schematic representation of the cylinder and illustrating a particular portion thereof having an excess of weight which requires neutralization.

Fig. 6 is an electrical diagram illustrating the action of the electronic tubes in response to the condition of unbalance represented by Fig. 5.

Fig. 7 is an electrical diagram illustrating the action of the tubes in accommodating a state of unbalance wherein counterbalance forces must be applied to more than one point of the cylinder.

Fig. 8 is a schematic representation of the cylinder illustrating the site of overweight to be such as to produce the conditions of Fig. 7.

Fig. 9 is a modified embodiment of the electrical circuit disclosed in Fig. 4.

Fig. 10 is a schematic circuit diagram which may be utilized in improving the precision of the counterbalance applications.

Fig. 11 is a view similar to Fig. 2 and illustrating further details of the weight receiving pockets schematically shown in Fig. 1.

The apparatus comprises an outer shell 15 supported by base 16 and having the usual valved water inlet 17 and the valved water outlet or dump 18. Within central openings formed in the end walls of shell 15 are disposed anti-friction

bearings 19 and 20 respectively supporting trunnions 21 and 22 of the washing cylinder 23.

Washing cylinder 23, apart from the peripheral pockets hereinafter disclosed, is of generally conventional form and is adapted to contain articles to be washed and damp-dried through the centrifugal extraction of water. Suitable doors 24 and 25, respectively formed in the shell 15 and washing cylinder 23 are arranged to register with each other so as to permit the introduction or withdrawal of articles from the washing cylinder 23.

Rotating motion is imparted to cylinder 23 by the variable speed electric motor 26, the pulley 27 of which drives a belt 28 so as to actuate the pulley 29 connected to the trunnion 22. As is conventional in apparatus of this type, the slower speeds of motor 26 serve to rotate the cylinder 23 at a slow or washing speed so that the articles are tumbled about the cylinder and become washed. The cylinder is provided with the usual ribs, not shown, for agitation or tumbling of the clothes.

After washing and one or more stages of rinsing, the rotating speed of cylinder 23 is increased, the dump 18 is opened and the centrifugal force resulting from the increased speed ejects the water from the washed clothes whereupon the water flows through the open dump 18 by means of the cylinder perforations 30.

After the clothes have been washed at the slow washing speed and the rotation of the cylinder has been increased for water extracting purposes, any unbalanced distribution of the articles in the cylinder will be manifested by vibration of the cylinder and shell. Such vibration is a source of noise, wear and danger. It is desirable, therefore, to correct the weight distribution so as to eliminate or neutralize the vibration. Accordingly, means are provided to inject compensation weight at selected portions of the cylinder 23 so as to equalize the distribution of weight therein. Such weight compensating means takes the form of water pockets 31, 32 and 33 equally spaced 120 degrees apart on the peripheral surface of the cylinder 23. It will be appreciated, however, that the number of water pockets may be varied as desired and will be spaced accordingly. Furthermore, the pockets may be formed within the conventional agitating ribs, not shown, such as the hollow hydraulic cylinder pockets shown in the application of Leo M. Kahn, Serial No. 610,035, now Patent #2,528,594, filed August 10, 1945.

The water pockets shown may be secured to the cylinder 23 by means of rivets, welding or any other suitable means of connection.

Means are provided to inject balancing weight material into the pockets selectively so as to differentially affect the balance of the cylinder. It will be apparent that such material injected into any one of the pockets will modify the peripheral weight distribution and apply a centrifugal force at the site of said one pocket. Trunnion 21 is formed with three concentrically arranged channels for applying water from water pipe 35 to selected pockets of the cylinder. Inner channel 36 is formed with a branch 37 and a continuation pipe 38 which connects with pocket 32 so as to introduce water thereto under specific conditions to be hereinafter described. Intermediate channel 39 is formed with a branch 40 and a continuation pipe 41 which connects with pocket 33 so as to similarly supply counterbalance fluid thereto. Outer channel 42 is formed with a branch 43 and a continuation pipe 44 which supplies the counterbalance fluid to pocket 31. The

connection or introduction of the continuation pipes to the pockets is illustrated in Fig. 1.

The water pockets are emptied after each complete operation or cycle preparatory to a succeeding operation as set forth in the above mentioned application Serial No. 620,038. For this purpose, discharge outlets 34 are provided in the end wall of each pocket, as shown in Figs. 3 and 11 in broken lines. Such discharge outlets 34 are disposed adjacent both longitudinal edges of the pockets inasmuch as exhaust water will naturally gravitate toward such edges because of the arcuate nature of the pockets as disclosed. The floors of the pockets which are comprised of the periphery of the cylinder may be concentric with the longitudinal axis of the cylinder but, in order to decrease the discharge time, the floors 32a may be sloping as shown in Fig. 11 and in the above mentioned prior patent application. It will be evident that when the cylinder stops rotating, centrifugal force will no longer maintain the injected water against the ceiling of the pockets but, on the contrary, it will flow down and through the discharge outlets 34.

Counterbalance fluid in the form of water is arranged, through any suitable source of water under pressure, to flow through pipe 35 into one or two of the valve openings 48, 49 and 50 respectively connected to the inner channel 36, the intermediate channel 39 and the outer channel 42. The face 51 of trunnion 21 is formed with three concentric troughs 52, 53 and 54 connected respectively with the valve openings 50, 49 and 48. The purpose of the concentric troughs is to permit water to flow from pipe 35 into a valve opening and thereafter into one of the water channels notwithstanding continued rotation of the cylinder. It will be understood that notwithstanding the radial position of the channels in respect to its complementary valve opening, water may nevertheless flow in any selected trough from the valve opening whereupon the water will flow into the channel which is connected to the selected trough. In this manner, the water receiving pockets will fill faster than would be the case were the channels to receive water from the valve openings only during such part of the rotation cycle when the selected channel was in alignment with the open valve.

Means are provided to select the course of site of the compensating fluid by selectively actuating the valves 56, 57 or 58 or any two of the valves according to the conditions to be corrected. Valves 56, 57 and 58 may comprise the armatures of solenoids 59, 60 and 61. It will be understood, therefore, that whichever of the solenoids are energized will determine the flow of the compensating fluid to the particular portions of the cylinder so as to modify the weight distribution thereof as required. The means for the selective actuation of the solenoids are provided in the electrical circuit hereinafter set forth.

The present apparatus applies compensating fluid to selected and spaced pockets during the rotation of the cylinder and in response to a specific condition of unbalance. It is necessary, therefore, that information be supplied not only concerning the presence of a predetermined degree of unbalance, but the portion of the cylinder where such unbalance exists so that corrective measures may be taken. Such corrective measures are, according to the instant invention, automatically put into effect when conditions so require. Means synchronized with the rotation of the cylinder are utilized to provide a reference voltage by which the instantaneous position of

particular portions of the cylinder may be identified or momentarily isolated. Thus the site of any unbalance can be located, the presence and degree of which is indicated by a vibration responsive device as hereinafter described. We have devised an electrical circuit which reacts to joint stimuli one of which is a reference voltage and instantaneously identifies or isolates the successive portions of the rotating cylinder while the other provides an indication of the degree of unbalance. Jointly, they produce a reaction in the circuit which is so timed by the reference voltage that the site of the correction is established thereby. Such reaction is arranged to energize one or more of the solenoids so as to open selected valves and introduce counterbalance fluid into selected peripheral portions of the cylinder during its rotation.

In order to determine the degree of unbalance, a magnetic, vibration pick-up device may be utilized. It is apparent, however, that any equivalent device such as a strain gauge pick-up may be used. It will be understood that the pick-up not only determines the degree of unbalance but correlates such information with the site of the unbalance depending upon the phase of the electrical signal produced by the pick-up. The output of the pick-up, as is well understood, is of substantially sine wave form produced pursuant to the vibrations of the cylinder in a condition of unbalance. A magnet 65, connected by bracket 66 to an external support is arranged to co-act with pick-up coil 68 so as to cause the induction of alternating voltages therein. An arm 69 having a contact 70 is spring pressed against the shaft 67 and connected so as to shift the coil 68 and cut the magnetic field in accordance with the vibration of the shaft. It will be recognized by those skilled in the art that the representation of the pick-up device in Fig. 1 is schematic and that any conventional apparatus such as a piezo-electric crystal pick-up may be employed.

The sine wave voltages as applied to the electrical lead wires 71 and 72 are fed to an amplifier 73 for the usual amplification purposes. Since the sine wave voltages may be of a low frequency, amplifier 73 may be of the direct coupled type or any amplifier adapted to accommodate currents of low frequency. These sine wave voltages are thereafter fed to a selector 74 which, as hereinafter described, is an electrical network having electronic tubes for selecting the valves to be actuated according to the information supplied to it in the form of electrical signals or intelligence. It is desirable to avoid actuation of the system by harmonics of the sine wave voltages if any are present. This may be accomplished, as will be recognized by those skilled in the art, by providing suitable filters in the input of amplifier 73. Since the unbalance correction need not be instituted until high speed rotation of the cylinder, the range of frequencies involved will not be very great and the filtering thereof may be easily effected.

Means are also provided to isolate or identify spaced peripheral portions of the rotating cylinder so as to correlate the information supplied thereby with that supplied by the vibration pick-up.

Referring to Fig. 4, a distributor disc 75 is mounted on the shaft 67 so as to rotate together with the cylinder 23. The distributor is arranged to successively apply electrical voltages to the brushes 76, 77 and 78. In the embodiment of Fig. 4, the power supply 79 may comprise a di-

rect current source in the order of 150 volts to which is connected the wiper arm 80. Arm 80 makes wiping contact with ring 81 which is of electrically conducting material. Integral with ring 81 is a voltage transmitting contact segment 82 which preferably, but not necessarily, occupies approximately 110 degrees of the ring 81 for purposes to be hereinafter described. As the distributor disc 75 rotates together with the cylinder 23, the 150 volts potential from power supply 79 is successively applied to each of the brushes as the segment 82 makes contact therewith.

Energizing means for each of the solenoid coils 59, 60 and 61 are provided in the form of electronic tubes 62, 63 and 64 of which the respective solenoid coils constitute the plate loads thereof. Tubes 62, 63 and 64 are preferably, but not necessarily, of the Thyratron type which are capable of handling large amounts of power. It will be apparent that voltages for the plates 65, 66 and 67 of each tube are applied respectively and successively by means of the brushes 77, 78 and 76. Suitable bias for the tubes may be employed and the grids thereof may be grounded through the usual high grid leak resistance, if desired. Two or more Thyratrons, or any number of gas-filled tubes, may be used in parallel for each solenoid, if necessary.

As the distributor disc 75 rotates, each tube will successively have plate voltage applied thereto at the same time that the amplified sine wave voltage from the vibration pick-up is applied to the grids thereof. This will set up a condition where the current flow in the plate circuit will be governed by the phase relationship of the grid and plate voltages. In one sense, it may be considered that the voltages applied to each plate are alternating. Since the phase of the grid voltage will depend upon the site of unbalance, variations of such site will vary the relative phase of the two voltages on each tube, that is, the relative time at which they reach their peak values. If the phase of the grid voltage lags the plate voltage by 180 degrees, the plate current will be entirely cut off. When both the grid and plate of any tube is positive, plate current will flow, the positive value of grid current depending upon the firing voltage in the tube as determined by its constants and the bias thereon. If in a modified circuit valve actuation is dependent upon negative grid voltage, the same principles will obtain as where the de-energization of a tube releases a relay or the like which closes the current to valve actuating means.

Referring to Fig. 5, the X marks a point in the loaded cylinder wherein an overweight exists. In order to establish balance, it is necessary to apply the material to pocket 32. Assuming, therefore, that the distributor disc 75 is so keyed to shaft 67 so that positive voltages are successively applied to the circuits controlling the application of counterbalance fluid to pockets 31, 32 and 33 in that order, each such circuit will be successively primed so as to conduct when the grid voltage reaches its positive firing value. Referring to Fig. 6, the square wave 85 may represent the plate voltage on tube 64 the solenoid winding 61 of which controls the armature valve 58 which in turn controls the application of counterbalance fluid to the pocket 31. After the distributor has moved approximately 110 degrees, the plate voltage to tube 64 will be cut off and approximately 20 degrees thereafter will be applied as square wave 86 to the plate 66 of tube 63 which controls the application of counterbal-

ance fluid to pocket 32. Similarly, square wave 87 is shortly thereafter applied to the plate 65 of tube 62, the voltage 88 having previously been removed from the plate 66. The cycle thereupon repeats itself as illustrated in Fig. 6. At the same time that the plate voltages are successively applied to the three tubes, the sine wave pick-up voltage generated by the vibration of the cylinder is applied to the grids 88, 89 and 90 of the respective tubes. The pick-up apparatus is so disposed on the shaft 67 in relation to the distributor connection thereto, that the grid voltage 91 generated pursuant to the unbalance at point X in Fig. 5, produces a trough at approximately the same time that voltage 85 is applied to plate 67. The crest of the grid voltage 91 appears during the period when voltage 86 is applied to tube 66. When voltage 87 is applied to the plate, voltage 91 is once more descending into its trough. The firing voltage 92 is that potential at which the grid must be in order to fire the tube at its conditions of operation. The values are well known to those skilled in the art and are determined as hereinabove set forth. Assuming that the firing grid voltage in a particular design of circuit is 10 volts of positive current, the tube 63 will fire when the grid voltage reaches the dotted line 92 representing the firing voltage. Considerable plate current will flow through the tube 63 so as to actuate the valve 57 and permit fluid from pipe 35 to be applied to the pocket 32. The fluid will therefore be correctly applied so that the cylinder approaches a condition of balance. It may be desirable if large degrees of unbalance are to be expected, to limit the amplitude of the grid voltage so that the width of its positive portion is not appreciably greater than that of the square wave plate voltage. As will be apparent to those skilled in the art, this may be done by a delayed automatic volume control (AVC) circuit in the amplifier, or by mechanical limiting means against the shaft 67.

The broken lines defining the grid voltage peak in Fig. 6 illustrate the simultaneous application of the vibration signal and plate voltage to tube 63. It will be understood that as the counterbalance fluid is unblocked from pocket 32 by the actuation of valve 57, the amplitude of the grid voltage will decrease as the vibration decreases pursuant to the correction of unbalance. When the amplitude is such as to descend below the firing voltage 92, the tube 63 will be extinguished notwithstanding the coincidence of the plate and grid voltages. It is a recognized characteristic of gas-filled tubes of the Thyratron type that mere removal of grid firing voltage does not per se produce tube extinction. However, our method of removing the plate voltage by the distributor means described insures proper extinction of the tubes since it is well known that the absence of plate potential will produce this effect. Thus, the present invention not only provides tubes capable of handling large amounts of power but automatically insures their proper operation by the same means which identifies or isolates the spaced peripheral portions of the cylinder through synchronous action therewith and by which is determined the instantaneous radial position of those portions.

It is desirable to decrease the angular sensitivity of the system to avoid overcompensation when a portion is so little overloaded as to be unobjectionable while predetermined grid voltage amplitude is being produced principally by an adjacent portion. For this reason, the seg-

ment 82 is preferably made less than 120 degrees so as to decrease the possibility of consequent erratic operation which might otherwise ensue. Referring to Fig. 6, if the grid voltage 91 were shifted slightly either to the left or right so as to overlap square wave 86 in regard to time or phase, it would not reach either of the adjacent plate voltages so as not to be coincident therewith. Accordingly, a margin is provided wherein corrective action is not taken so that the angular sensitivity is decreased thereby. When, however, the pocket 32 has been supplied with sufficient counterbalance fluid to represent a force of the necessary magnitude, the total vibration will be so little that the firing voltage line 92 will not be reached and compensation will cease.

Since the tubes will successively extinguish as the distributor rotates, under ordinary conditions the valves would be de-actuated between firing periods so that counterbalance fluid would only flow when the tube was firing and the water would therefore flow in spurts. In order to eliminate such periodic action, means are taken to continue the energization of the solenoids for a period after the tube associated therewith has been extinguished and until the tube re-fires when the plate voltage is re-applied thereto.

Accordingly, hold-over circuits in the form of condensers 95, 96 and 97 are connected across the respective solenoid windings. The distributor action will charge each condenser each time that plate voltage is applied to the tube associated therewith. When the source of voltage is removed, the condenser will maintain energization of the solenoid by discharging therethrough. The value of condensers 95, 96 and 97 will be chosen so as to produce a time constant network which is correlated with the speed of cylinder rotation. It will be apparent that if the cylinder rotates three times a second, for example, the time constant may be in the order of one-third of a second and the hold-over circuit elements will be selected according to well known standards. By this means, when the correct pocket or pockets have been selected for the introduction of counterbalance material, the application of such material will be continued to such pocket until balance is achieved notwithstanding the periodic extinction of the tube which controls its valve.

In Fig. 8, the X marks a point in the loaded cylinder wherein an overweight exists. In order to establish balance in such a condition, it is necessary to apply the counterbalance material simultaneously to pockets 31 and 32. Referring to Fig. 7, it will be seen that the phase of the plate voltages remains fixed, being in the same phase as illustrated in Fig. 6. This, of course, is because the keying of the distributor disc 15 to shaft 67 remains undisturbed and at all times thereafter determines the phase of the plate voltages. The grid voltage 99 has, however, shifted approximately 45 degrees as determined by the respective X points in Figs. 5 and 8, so that the positive peak of the grid voltage is coincident with both plate voltages 86 and 87. Accordingly, both tubes 62 and 64 will fire whereupon the consequent actuation of valves 56 and 58 will effect the introduction of counterbalance material to the pockets 31 and 32 simultaneously. It will be understood, therefore, that more than one, but less than all of course, of the pockets may be filled simultaneously in response to a condition of unbalance.

Whereas a cylinder having three pockets has

been shown, it will be obvious that many more such pockets may be provided if finer degrees of balance are to be accomplished. In such cases, the distributor would be provided with a contacting segment of an extent commensurate with the division of the number of pockets into 360 degrees as will be evident. Furthermore, other methods of applying the plate voltages may be employed, such as that of a pilot generator which produces plate voltages from the rotation of the cylinder itself and eliminates the necessity of a power supply.

In Fig. 9 is illustrated a modified embodiment of the selector circuit wherein ordinary vacuum tubes may be employed. In this case, the plate voltages are constantly applied to the tubes 100, 101 and 102. However, the vibration pick-up grid voltages are distributed to the grids 103, 104 and 105 through the distributor disc 106. The wiper arm 107 is connected to one terminal of the amplified vibration pick-up voltage, the other terminal of which may be suitably grounded. The contact segment 108 receives the grid voltages and applies them through the brushes 109, 110 and 111 to the grids as aforesaid. As before, the phase of the grid voltage will depend upon the site of unbalance. As this voltage is distributed to the grids, it is broken up into three components one or more of which, but less than all, will include the positive portion of the grid voltage. The bias of each tube is arranged as by cathode bias resistors 114, 115 and 116 so that the tube will conduct at a predetermined grid potential. Conventional means are provided to maintain the tubes normally at or near their cut off state so that the solenoids 117, 118 and 119 are not energized. However, whichever of the tubes receives the positive portion of the pick-up signal of proper amplitude will conduct so as to open the correct valves and approach or effect balance as hereinabove described. The usual grid leak resistors 120, 121 and 122 are provided and the holdover condensers 123, 124 and 125 form a time constant network therewith for the purposes above described. Since tubes 100, 101 and 102 are not of the gas-filled type, they may be cut off without removing the plate voltage but ordinarily such tubes, unless made very large, can not handle adequate power. Accordingly, it may be desirable to provide a plurality of such tubes in parallel, or the solenoids 117 et seq may take the form of relays for closing another power circuit which will suitably actuate the necessary valves.

In Fig. 10 is illustrated an additional safeguard for eliminating a possibility of erratic operation or hunting in the apparatus. For example, should a pocket overfill due to lag in operation of any solenoid, the site of unbalance would be shifted to a diametrically opposite point and further correction would be made by applying the fluid to different pockets. It is desirable, however, to provide a margin of tolerance whereby a slight over-correction will not shift the application of counterbalance fluid. The firing voltage level 92 is ordinarily set by the bias on the grids 88, 89 and 91 of the valve control tubes. Such bias may be applied to the grids through a spring arm 130 having a contact point 131 which normally makes electrical contact with terminal 132 which is connected to a negative point of voltage 133. However, when any one of the valves 56, 57 or 58 is actuated, it lifts arm 130 so that contact 131 removes the bias of point 133 and contact 134 is caused to meet arm 135

which is connected to a less negative voltage point 136. Correction will thereupon continue until the pick-up voltage is so low that it does not reach the firing voltage line represented by the lower firing voltage point 136. After correction has been established and the actuated valve has returned to normal position, the arm 130 will likewise be restored to normal position and the higher bias will then be applied so that a slight overflow will not produce sufficient amplitude of firing voltage to strike at the new point of operation. This feature will be further useful in avoiding erratic operation as the water is extracted from the clothes during the extracting process so as to change the weight distribution. However, since the great bulk of the water is extracted during the beginning of the extracting operation and since proper balancing has been initially approached, subsequent unbalance will be of considerable less importance.

We have shown a preferred embodiment of our invention, but it is obvious that numerous changes and omissions may be made therefrom without departing from its spirit. For example, while we have illustrated the achievement of balance through the addition of counterbalance fluid to selected sites on the periphery of the cylinder, it will be apparent that the invention can be adapted toward the release of fluid from a normally filled pocket. In other words, the vibration responsive device would be so situated with respect to the distributor contact segment that a valve of a receiving element at the site of unbalance would be actuated so as to release water from the pocket at that site. Obviously a source of water supply from the pipe 35 will not be required in such an embodiment and the release of water will serve to modify the peripheral weight distribution of the cylinder. Furthermore, since the invention is adapted toward the release of fluid from a normally filled pocket, it is possible to provide balancing apparatus in a two pocket cylinder. In such a structure it would be unnecessary to provide the water-tight bearing means illustrated in Figs. 2 and 3 hereof since the counterbalance fluid may be removed or applied centrally of the trunnions. A structure illustrating a cylinder with two diametrically opposed water receiving pockets and providing for the application of fluid thereto through the cylinder trunnions is illustrated in the above mentioned sole patent application of Leo M. Kahn Serial No. 620,038. However, in an embodiment constructed according to the instant invention, the two pockets would be spaced 90 degrees apart on the cylinder and the balance may be achieved by providing means for both adding water and releasing water selectively from either pocket. It will be recognized that the provision for either removing or releasing water from a pocket wherein two pockets spaced at 90 degrees are provided, is equivalent to providing four pockets spaced at 90 degrees wherein counterbalance fluid can be either removed or applied, but not both. As regards the use of a pilot generator mentioned above, it will be recognized by those skilled in the art that the generator would produce a reference sine wave voltage instead of the square waves produced by the distributor. However, the phase of the reference sine wave would be correlated with the position of the cylinder so as to similarly serve as identification means for its peripheral portions. By applying the phases of the pilot gen-

11

erator and vibration pick-up to a phase sensitive device, the necessary corrective action can be taken. For example, one voltage can be applied to the stator of a "Selsyn" motor and one to the rotor whereupon the rotor would turn to a position depending upon the phase relationship. A contact disc on the rotor so as to rotate therewith may selectively close electrical circuits for actuating the proper valves.

As will be apparent to those skilled in the art, the amplifier 13 will be capable of gain adjustment so that the unbalance indications can be amplified as desired. Similarly, the bias on the tubes may be adjusted depending upon the level at which correction is desired.

We claim:

1. Balancing apparatus for a rotating cylinder for housing wet articles from which liquid is to be centrifugally extracted, comprising a series of counterweight receiving elements located at spaced peripheral portions of said cylinder, means to feed liquid counterweight material to said receiving elements, inlet controls for blocking said material from said receiving elements, control operating means for selectively unblocking at least one of said receiving elements so as to introduce said counterweight material thereto, a vibration responsive device for producing a series of electrical response pursuant to vibrations of said rotating cylinder, means synchronized with its rotation for successively establishing the instantaneous angular position of said spaced portions of said cylinder, and means jointly controlled by said series of electrical responses and by said synchronized means for actuating said control operating means.

2. Balancing apparatus for a rotating cylinder for housing wet articles from which liquid is to be centrifugally extracted, comprising a series of counterweight receiving elements located at spaced peripheral portions of said cylinder, means to feed counterweight material to said receiving elements, inlet controls for blocking said material from said receiving elements, inlet control operating means for selectively unblocking at least one of said receiving elements so as to introduce said counterweight material thereto, a vibration responsive device for producing an electrical voltage of substantially sine wave form pursuant to vibrations of said rotating cylinder, means synchronized with its rotation for successively establishing the instantaneous angular position of said spaced portions of said cylinder, and means jointly controlled by the amplitude of a predetermined portion of said sine wave voltage and by said synchronized means for actuating said unblocking means.

3. Balancing apparatus for a rotating cylinder comprising a plurality of weight receiving elements adapted to receive weight counterbalance material from a source thereof, control means for selectively applying said material to control said receiving elements, said weight receiving elements being respectively disposed in spaced portions of said cylinder so as to differentially affect the balance thereof when said counterbalance material is selectively applied thereto, a vibration responsive device adapted to produce a first electrical output pursuant to the vibration of the rotating cylinder, said control means comprising normally inactive electronic tubes associated with each of said receiving elements, plate and grid electrodes in said electronic tubes, means to successively elec-

trically establish the angular positions of said weight receiving elements of said rotating cylinder so as to produce a series of second electrical outputs each correlated with a specific weight receiving element of said cylinder and means to apply both a predetermined controlling portion of said first electrical output and one of said series of second electrical outputs to at least one of said electronic tubes in said control means so as to actuate said one electronic tube when a predetermined degree of vibration exists in said rotating cylinder whereby counterbalance material is applied to the receiving element associated with said one electronic tube, other portions of said first electrical output being applied to other tubes so as to continue said other tubes in their normally inactive state.

4. Balancing apparatus according to claim 3 including valves controlled by said control means for introducing counterbalance material to said receiving elements, and solenoids in the plate circuits of said electronic tubes, said solenoids being operative to actuate said valves whereby said material may flow into said receiving elements when the electronic tube associated therewith is actuated so as to energize the solenoid in its plate circuit.

5. Balancing apparatus according to claim 3 including valves controlled by said control means for introducing said counterbalance material to said receiving elements, solenoids in the plate circuits of said electronic tubes, said solenoids being operative to actuate said valves whereby said material may flow into said receiving elements when the electronic tube associated therewith is actuated so as to energize the solenoid in its plate circuit and a hold-over device in the plate circuit of each electronic tube so as to maintain energization of its solenoid after the electronic tube associated therewith is de-actuated.

6. Means for balancing vibration in a rotating cylinder comprising a plurality of weight receiving elements adapted to selectively receive counterbalance weight material, from a source thereof, control means for selectively applying said material to said receiving elements, a vibration responsive device adapted to produce an electrical output pursuant to vibration of the rotating cylinder, said plurality of weight receiving elements being respectively disposed in spaced peripheral portions of said cylinder so as to differentially affect the balance thereof when counterbalance material is selectively applied thereto, valves included in said control means for controlling the application of said material to said receiving elements, an electronic tube circuit for each of said valves, each said electronic tube circuit being associated with one of said receiving elements, each tube in said circuits having at least plate, grid, and cathode electrodes, a source of plate potential, distributor means synchronized with the rotation of said cylinder for successively applying said potential to the plates of said tubes, means for simultaneously applying the output of said vibration responsive device to the grids of said tubes, said tubes being responsive to a predetermined coincidence of voltage conditions on their respective plates and grids for actuating said valves so as to apply said material selectively to said receiving elements.

7. Balancing apparatus according to claim 6 wherein said vibration responsive device electrical output is a sine wave, and said coincidence

of voltage conditions comprises the simultaneous application of a positive portion of said sine wave of predetermined amplitude on any grid of said tubes and application of plate potential to said tube whereby the selected actuation of valves in said control means depends upon the phase relationship of the grid and plate voltages.

8. Balancing apparatus according to claim 6 wherein said vibration responsive device electrical output is a sine wave, and said coincidence of voltage conditions comprises the application of a positive portion of said sine wave and of a predetermined amplitude thereof on the grid of any of said tubes, and the simultaneous application of plate voltage to the plate of said tube, whereby the selected actuation of valves in said control means depends upon the phase relationship of the grid and plate voltages, the application of voltages to the plates being synchronized with the rotation of said cylinder so as to have a relatively constant phase, said grid voltage having a varying phase depending upon the site of unbalance, the frequency of the grid voltage being lower than that of the plate voltage in proportion to the number of receiving elements in the apparatus, said number being at least three so that said conditions of coincidence may occur in more than one tube whereby more than one receiving element may be supplied with said counterbalance weight material at any one time.

9. Balancing apparatus according to claim 6 wherein said tubes comprise gas-filled electronic tubes adapted to fire under predetermined conditions of grid voltage and wherein said vibration responsive device electrical output is a sine wave, and said coincidence of voltage conditions comprises the application of a positive portion of said sine wave and of a predetermined amplitude thereof on the grid of any of said tubes and the simultaneous application of plate voltage to the plate of said tube, whereby the selected actuation of valves in said control means depends upon the phase relationship of the grid and plate voltages, the application of voltages to the plates being synchronized with the rotation of said cylinder so as to have a relatively constant phase, said grid voltage having a varying phase depending upon the site of unbalance, said phase variation of grid voltage with respect to plate voltage being such that said conditions of coincidence may occur in more than one tube whereby more than one gas-filled tube may fire simultaneously and more than one receiving element may be supplied with said counterbalance weight material at one time.

10. Balancing apparatus according to claim 6 wherein said vibration responsive device electrical output is a sine wave, and said coincidence of voltage conditions comprises the application of a positive portion of said sine wave and of a predetermined amplitude thereof on the grid of any of said tubes and the simultaneous application of plate voltage to the plate of said tube, whereby the selected actuation of valves in said control means depends upon the phase relationship of the grid and plate voltages, the application of voltages to the plates being synchronized with the rotation of said cylinder so as to have a relatively constant phase, said grid voltage having a varying phase depending upon the site of unbalance, said phase variation and frequency of grid voltage with respect to plate voltage being such that said conditions of coincidence may occur in more than one tube whereby more than one receiving element may be supplied with said

counterbalance weight material at any one time, and hold-over means in each electronic tube circuit whereby an actuated valve may remain actuated after plate potential is removed from its associated electronic tube, said hold-over means having a value correlated with the rotation of said cylinder whereby said distributor means restores said coincidence of voltage conditions to said tube before said valve is de-actuated.

10 11. Balancing apparatus according to claim 6 including means to separate the successive applications of plate potential to the plates of said tubes whereby said voltage condition on a grid may overlap the plate voltage in a tube in extent of time without being brought into time coincidence with the plate voltage of an adjacent tube.

15 12. Balancing apparatus according to claim 6 including means to separate the successive applications of plate potential to the plates of said tubes whereby said voltage condition on a grid may overlap the plate voltage in a tube in extent of time without being brought into time coincidence with the plate voltage of an adjacent tube, said means to separate the successive applications

20 comprising a series of radial segments on said distributor means, each of said segments being connected to the respective plates of said tube and having plate potential successively applied thereto so as to successively transfer such potential to said plates, said segments occupying an arcuate area of less than a predetermined fraction of 360 degrees, said fraction resulting from a division of 360 degrees of cylinder periphery by the number of receiving elements thereon.

25 13. Means for balancing vibration in a rotating cylinder comprising a plurality of weight receiving elements adapted to selectively receive counterbalance weight material, from a source thereof, control means for selectively applying said material to said receiving elements, a vibration responsive device adapted to produce an electrical output of sine wave form pursuant to vibration of the rotating cylinder, said plurality of weight receiving elements being respectively disposed in spaced peripheral portions of said cylinder so as to differentially affect the balance thereof when counterbalance material is selectively applied thereto, valves included in said control means for controlling the application of said

30 40 material to said receiving elements, an electronic tube circuit for each of said valves, each said electronic tube circuit being associated with one of said receiving elements, each tube in said circuits having at least plate, grid and cathode electrodes, a potential supply for the plates of said tubes, distributor means synchronized with the rotation of said cylinder for successively applying portions of the sine wave output of said vibration responsive device to the grids of the tubes

45 50 60 whereby each grid receives an equal portion of said sine wave, the positive portion of said sine wave being limited to less than all of said grids, said positive portion being operative to actuate the tube, the grid of which it is applied to, whereby the valve associated with said tube is actuated so as to apply said material selectively to said receiving elements.

70 14. Balancing apparatus for a rotating cylinder comprising a vibration responsive device adapted to produce a first electrical output pursuant to vibrations of the rotating cylinder, means to electrically establish the angular position of spaced portions of said cylinder during its rotation so as to produce a second electrical output thereby, means jointly actuated by a pre-

15

determined level of said first electrical output and by said second electrical output for applying a counterbalance force to said cylinder as determined by both a predetermined extent of unbalance indicated by said first electrical output and the site of said unbalance as determined by said second electrical output, and means to increase the actuating level of said jointly actuated means after a counterbalance force has been applied whereby said vibrations must rise to a substantially higher amplitude after such application in order to resume the application of counterbalance forces thereby.

15. Balancing apparatus for a rotating cylinder for housing wet articles from which liquid is to be centrifugally extracted, said cylinder comprising a plurality of weight receiving elements arranged to contain quantities of counterbalance material, control circuit means for automatically regulating the quantity of such material in the respective elements, said receiving elements being respectively disposed in angularly spaced peripheral portions of said cylinder so as to differentially affect the balance thereof depending upon the quantities of counterbalance material contained in the respective receiving elements, an electrically controlled vibration responsive device adapted to produce an electrical signal pursuant to the site of overweight of said articles in the rotating cylinder, said control circuit means being automatically actuated by said electrical signals so as to vary the counterbalance material contents of at least one of said receiving elements during a state of unbalance of the rotating cylinder, said control circuit means being continuously operable during rotation of said cylinder and during gradual liquid extraction of said articles so as to continue the automatic varying of said contents as said site of overweight may shift.

16. Balancing apparatus for a rotating cylinder for housing wet articles from which liquid is to be centrifugally extracted, comprising a vibration responsive device arranged to produce an indication of unbalance pursuant to vibrations of the rotating cylinder, inlet control means to supply counterbalance material from a source thereof to spaced peripheral portions of said rotating cylinder, rotating means for successively establishing the angular position of said spaced portions of the rotating cylinder, inlet control actuating means jointly controlled by said vibration responsive device and said rotating means for selectively actuating said inlet control means so as to supply said material to one or more of said spaced portions, and a hold-over member to continue supplying said material to said one or more of said spaced portions during continued rotation of said cylinder.

17. Balancing apparatus for a rotating cylinder for housing wet articles from which fluid is to be centrifugally extracted, comprising a plurality of weight receiving elements arranged to receive weight counterbalance material from a source thereof, control means for selectively applying said material to said receiving elements, said weight receiving elements being respectively disposed in spaced peripheral portions of said cylinder so as to differentially affect the balance thereof when said counterbalance material is selectively applied thereto, a vibration responsive device arranged to produce a first electrical output pursuant to the vibration of the rotating cylinder, means to successively electrically establish the angular position of the weight receiving

16

elements of said rotating cylinder so as to produce a cyclical series of second electrical outputs corresponding to such angular position, said control means being connected to receive said first and second electrical outputs and being actuated jointly by a time coincidence of said first electrical output and less than all of the second electrical outputs of any one cycle so as to apply said material to at least one of said receiving elements selected according to the amplitude of vibration occurring during the establishment of the angular position of one or more receiving elements.

18. Balancing apparatus according to claim 15, including means to continue said application of said material to said selected receiving elements during continued rotation of said cylinder and subsequent establishment of the angular position of the remaining receiving elements by said series of second electrical outputs.

19. Balancing apparatus according to claim 17 including an electrical hold-over network of a value correlated to the speed of rotation of said cylinder whereby said joint actuation of said control means is held over between periods when the electrical output establishing the angular position of selected receiving elements is applied, coincidental with said first electrical output, to said control means.

20. Balancing apparatus for a rotatable hollow cylinder of a machine for treating discrete articles comprising a plurality of weight receiving elements arranged to house varying amounts of weight counterbalance material, said weight receiving elements being angularly disposed around said cylinder so as to differentially affect the balance thereof pursuant to the varying amounts of said material housed therein, inlet control means including an electrical circuit for selectively varying the amounts of said material housed in said receiving elements, a vibration responsive device arranged to provide an electrical voltage pursuant to the passage of an overweighted portion of the rotating cylinder, and

25 reference means continuously operative during the rotation of the cylinder for registering the momentary angular disposition of each weight receiving element, said inlet control means being controlled jointly by said vibration responsive device electrical voltage and the action of said reference means so as to vary the amounts of said material in one or more of said weight receiving elements depending upon the site of said overweighted portion.

21. Balancing apparatus for a rotatable hollow cylinder comprising a plurality of weight receiving elements arranged to receive counterbalance liquid from a source thereof, said weight receiving elements being respectively disposed adjacent spaced peripheral portions of said cylinder

30 so as to differentially affect the balance thereof when said liquid is selectively applied thereto, inlet control means for selectively applying such liquid to such receiving elements, a vibration responsive device arranged to provide an electrical voltage at a time coinciding with the passage of an overweighted portion of the rotating cylinder, reference means operative by the rotation of the cylinder for registering the momentary angular disposition of each weight receiving element, said control means being activated jointly by said vibration responsive device and said reference means so as to apply said liquid to one or more of said weight receiving elements which are in a portion of said cylinder substantially opposed

to said overweighted portion, and a hold-over element acting on said control means whereby said control means acts to continue the application of said liquid after the joint control thereof terminates.

22. Balancing apparatus for a rotatable hollow cylinder comprising a plurality of weight receiving elements arranged to receive counterbalance liquid from a source thereof, said weight receiving elements being respectively disposed adjacent spaced peripheral portions of said cylinder so as to differentially affect the balance thereof when said liquid is selectively applied thereto, an inlet and inlet control means for each weight receiving element including an electrical circuit for selectively applying such liquid to said receiving elements, a vibration responsive device arranged to produce an electrical voltage having one voltage peak during each revolution of the rotating unbalanced cylinder and occurring at a time coinciding with the passage of an overweighted portion of the rotating cylinder, reference means for establishing the identity of any one of said receiving elements as the receiving element passes a predetermined line during its rotating travel, said reference means being operative to produce a series of voltage peaks each corresponding to one of said receiving elements, said reference means voltage peaks successively following each other in time and having a higher frequency than said vibration voltage whereby the time duration of said vibration voltage peak may cause it to overlap more than one reference means voltage peak depending upon their phase relationship, said inlet control means being operated by a time coincidence of a vibration voltage peak and a reference means voltage peak so as to apply said liquid to the receiving element whose reference means voltage peak coincides with the vibration voltage peak in any one rotation of the cylinder, whereby the liquid may be simultaneously fed to more than one receiving element.

23. Apparatus according to claim 22, wherein said vibration voltage is of substantially sine wave form and of the same frequency as that of the rotating cylinder so that its peak occupies almost one half of the rotating cycle, said reference means voltage peaks being at least three in number and being equally spaced through said rotating cycle.

24. Balancing apparatus for a rotatable hollow cylinder comprising a plurality of weight receiving elements arranged to receive counterbalance liquid from a source thereof, said weight receiving elements being respectively disposed adjacent spaced peripheral portions of said cylinder

der so as to differentially affect the balance thereof when said liquid is selectively applied thereto, an inlet and inlet control means for each weight receiving element including an electrical circuit for selectively applying such liquid to said receiving elements, a vibration responsive device arranged to provide an electrical voltage having one voltage peak during each revolution of the rotating unbalanced cylinder and occurring at a time coinciding with the passage of an overweighted portion of the rotating cylinder, reference means for establishing the identity of any one of said receiving elements as the receiving element passes a predetermined line during its rotating travel, said reference means being operative to produce a series of voltage peaks each corresponding to one of said receiving elements, said reference means voltage peaks successively following each other in time and having a higher frequency than said vibration voltage whereby the time duration of said vibration voltage peak may cause it to overlap more than one reference means voltage peak depending upon their phase relationship, said inlet control means being operated by a time coincidence of a vibration voltage peak and a reference means voltage peak so as to apply said liquid to the receiving element whose reference means voltage peak coincides with the vibration voltage peak in any one rotation of the cylinder, whereby the liquid may be simultaneously fed to more than one receiving element.
